US0D1087159S

(12) **United States Design Patent** (10) Patent No.: **US D1,087,159 S**
(45) Date of Patent: ** Aug. 5, 2025

(54) **DISPLAY SCREEN OR PORTION THEREOF
WITH GRAPHICAL USER INTERFACE**

(71) Applicant: **Apple Inc.**, Cupertino, CA (US)

(72) Inventors: **Lee Broughton**, Santa Cruz, CA (US); **Alan C. Dye**, San Francisco, CA (US); **Jonathan P. Ive**, San Francisco, CA (US); **Behkish Johnnie Manzari**, San Francisco, CA (US); **Pani Page**, Las Vegas, NV (US); **Grant R. Paul**, San Francisco, CA (US); **William A. Sorrentino, III**, San Francisco, CA (US); **Andre Souza Dos Santos**, San Jose, CA (US); **Christopher Wilson**, San Francisco, CA (US)

(73) Assignee: **Apple Inc.**, Cupertino, CA (US)

(**) Term: **15 Years**

(21) Appl. No.: **29/951,109**

(22) Filed: **Jul. 8, 2024**

Related U.S. Application Data

(63) Continuation of application No. 29/807,518, filed on Sep. 13, 2021, now Pat. No. Des. 1,034,633, which is a continuation of application No. 29/694,349, filed on Jun. 10, 2019, now Pat. No. Des. 930,661, which is a continuation of application No. 29/616,884, filed on Sep. 9, 2017, now Pat. No. Des. 851,111.

(57)

CLAIM

The ornamental design for a display screen or portion thereof with graphical user interface as shown and described.

DESCRIPTION

The FIGURE is a front view of a display screen or portion thereof with graphical user interface showing the claimed design.

The broken lines in the FIGURE show a display screen or portion thereof, and form no part of the claimed design.

1 Claim, 1 Drawing Sheet
